DEVICE FOR FOLDING STRIPS

Margaret F. Currie, Manhasset, N. Y.

Application August 7, 1952, Serial No. 303,111

4 Claims. (Cl. 270—93)

This invention relates to an improved device for folding flexible sheet material, in strip form, capable of being creased, folded or shaped. It is especially adapted for folding textile fabrics to form bands, edging, reinforcements, ribbons or the like. The device is simple and is readily handled by the home seamstress. Folded fabric strips of the type referred to are of value in numberless utilitarian and ornamental uses. They are of common occurrence in wearing apparel, household articles, draperies, and in many other situations. The folded strips are formed, according to the present invention, by placing a flat strip on the device, turning a marginal portion of the strip under and engaging it with a guide member, and drawing the strip through the device to form a continuous fold on one or both margins of the strip, as subsequently described more in detail.

This application is a continuation-in-part of the present inventor's copending United States patent application Serial No. 291,881, filed June 5, 1952, now U. S. Patent No. 2,708,113. It was there stated that bands and the like are available on the market in rolls. If bought in substantial quantity, they are costly. Moreover, even aside from the expense, the products on the market often are not available in the desired material or color. With the device of the application referred to, and with the present invention, a decided advantage can be secured by using a part of the seamstress' stock material to make bands matching the main work.

The present invention is in some respects more advantageous than that of the application referred to, especially in that it has somewhat greater accuracy in preparing narrow bands or the like and is simpler to manufacture.

Referring to the drawings:

Fig. I is a perspective view of one form of the invention;

Fig. II is a transverse sectional view, showing the parts of the device of Fig. I in partially folded position and a strip of fabric in the device;

Fig. III is a fragmentary enlarged sectional view, showing the device rolled into operative position with the fabric strip folded and ready to be pulled through the device;

Fig. IV is a perspective view corresponding to Fig. III;

Fig. V is a perspective view of another form of the invention;

Fig. VI is an enlarged fragmentary sectional view taken at the forward edge of the base of the device of Fig. V and showing a fabric strip in position;

Fig. VII is a view corresponding to Fig. VI, except that Fig. VII shows the parts of the device fully assembled and in position for forming folds in a strip of material; and

Fig. VIII is a perspective view of a modified form of guide member.

Referring first to Figs. I to IV of the drawing, reference numeral 1 denotes a base which is foldable along the junctures denoted by 2, 3 and 4. Base 1 is preferably

2

made of glazed paper, metallic cloth, or other material which is flexible yet has some degree of rigidity and is capable of withstanding moderate heat. A shaping means, shaper, or guide 5 is secured to base 1 in any suitable manner; in the form shown, it is attached to base 1 by two rows of stitching 6 and 7. Guide 5 may be made of cardboard or equivalent material which has sufficient flexibility to permit insertion, between guide 5 and base 1, of the overturned margins 8 and 9 of a fabric strip 10. Base 1 may be regarded as formed of four jointed sections, the first section being adapted to serve as the base proper (1b), a second section 5' which carries guide 5, a third section 1c adapted to be turned over the guide, and a fourth section 1a adapted to be turned to rest against base 1b, as shown in Fig. III.

The form of the invention shown in Figs. V to VII differs from the foregoing principally in that the strip to be folded is held against the upper edge of a base 11, instead of within the area of the base, as in the device of Figs. I to IV. Base 11 carries a folder or holding member 12. Base 11 is preferably made of rather heavy cardboard, metal, plastic, or the like, having the mentioned qualities of some rigidity and heat resistance. Holding member 12, which is flexible, carries a guide 13, which may be secured to holding member 12 in any suitable way, as by glue or stitching.

Fig. VIII shows a variant form of guide, comprising a steel strip 15, or equivalent member, firmly fastened in holding member 12'. This member may be folded over to form a tubular pocket 17, which is then stitched or otherwise fastened to form a carrier for strip 15. Pocket 17 is stitched in such a way as to leave the edge portions free to receive therebeneath the folded margins of the strip of fabric, in the same general manner as guide 5 is mounted in the device of Figs. V-VII. This form of guide may be substituted for the one shown in Figs. V-VII.

In using the form of the invention shown in Figs. I to IV, assuming that a band folded under on both sides is to be made, the operator cuts a strip of fabric 10 to a width equal to the width of guide 5 plus the distance between rows of stitching 6 and 7 and the respective adjacent sides of guide 5. The operator then slips the edges of fabric strip 10 under guide 5 so that the inner edges of the turned over portions of the fabric strip abut approximately against the rows of stitching 6 and 7. The strip, prior to folding, is shown at 10a in Fig. IV entering the device. By folding over the jointed parts above referred to, the device assumes the form shown in Figs. III and IV. Now the operator pulls the strip of fabric through the device. The strip comes out accurately creased or folded on both sides.

When using fabrics that hold a crease readily, no additional creasing or folding effect is needed. The fold will stay until there is opportunity to sew or otherwise set the fold in position. When using fabrics which crease with difficulty, it is best to place a warm flat iron upon or near the upper side of the device. The heat will set the crease as the strip is pulled through.

It is readily possible to operate the device in many cases without securing it to a board, table or other fixed support. The operator merely grasps the projecting ends of the base with one hand and pulls the strip through with the other hand. For some purposes, especially when a flat iron is used, after the fabric strip is placed in position on guide 5, the base should be secured to a fixed object, as by thumb tacks or other means, which leaves both the operator's hands free to pull the fabric and handle the iron.

The width of the strip fed to the device is important. The instructions provided with the device when sold may state that the width of the strip to be used in the device

is the same as the width of the first section 1a of base 1 and that this should be used as a guide in cutting the strip. Obviously, the invention is not dependent on any particular way of forming the strip nor on the precise width; for best results, however, it should have the width stated. The device is primarily intended for handling one width of strip only. In view of the simplicity of the device, it is easy to supply a set enabling the seamstress to prepare bands and the like of a variety of widths.

The operation of the device shown in Figs. V to VIII is similar to that just described. It is particularly advantageous when narrow bands or the like are to be made. Guide 13 is mounted with sufficient flexibility to permit insertion of the turned under margins of the fabric strip to be folded. The strip is placed on the device and the margins of the strip overlying guide 13 is tucked in so that the free edges abut against the stitching 14. Holding member 12 is then pulled around the forward edge of base 11, and this action presses guide 13 and the folded fabric strip which it carries, against base 11. The operator then holds the base in one hand, or fastens the device to a board or the like, and pulls the strip of fabric through to form the folded strip.

Although the primary purpose of the invention is to facilitate the work of the home seamstress, the invention may be embodied in machine form for commercial production of bands and the like.

The principle on which my invention operates is exemplified by the foregoing examples of preferred embodiments, which may be varied to some extent without departing from that principle.

I claim:

1. A fabric folding device comprising a plurality of sections of generally rectangular form connected respectively one with another along transverse lines to form a folder, a shaper of generally rectangular form transversely mounted for lengthwise bi-marginal flexibility on one of said sections to receive marginal portions of a strip of fabric between said shaper and said section, another of said sections being foldable to compress fabric

10 30 35 40

on said shaper while permitting motion of said fabric, whereby upon drawing said strip of fabric forwardly in contact with said shaper, said strip emerges in folded form.

5 2. A fabric folding device according to claim 1, in which the folder comprises four flexibly joined sections, the first section is adapted to serve as a base, the shaper is mounted on the second section, and the third and fourth sections are foldable under said second section to form an assembly which may be compressed against the first section to hold said fabric in slidable relation to said shaper.

15 3. Apparatus according to claim 2, in which said shaper is mounted on the upper side of said second section by longitudinal means spaced inwardly from the edges of said shaper so as to permit limited elevation of said edges to receive therebeneath portions of the fabric strip.

20 4. A fabric folding device comprising four flexibly joined sections, a shaper mounted on the second of said sections, and adapted to receive the folded margins of a portion of a strip of fabric to be folded, the third and fourth of said sections being foldable under said second section to form an assembly, which may be compressed against the first section to hold said fabric in slidable relation to said shaper, whereby when the fabric is drawn forwardly with respect to said shaper, the fabric emerges therefrom in folded form.
